UNITED STATES PATENT OFFICE.

CHARLES C. ALEXANDER, OF BAYONNE, NEW JERSEY, ASSIGNOR TO DAVIS
REID & ALEXANDER, OF NEW YORK, N. Y.

DESIGN FOR A TILE.

SPECIFICATION forming part of Design No. 25,109, dated January 28, 1896.

Application filed November 15, 1895. Serial No. 569,115. Term of patent 14 years.

To all whom it may concern:

Be it known that I, CHARLES C. ALEXANDER, of Bayonne, in the county of Hudson and State of New Jersey, have invented and produced a new and original Design for Tiles, 5 of which the following is a full, clear, and exact description.

Reference is to be had to the accompanying drawings, forming a part of this specification, 10 in which—

Figure 1 is a face view of a tile, showing my design; and Fig. 2 is a sectional side elevation of the same.

The essential feature of my design consists

in circular disks A, embedded in the binding material B, and arranged one alongside the other, and with their peripheral surfaces in contact to form on the face of the tile triangular figures C, of the material B, between adjacent disks A. 15 20

I claim—

The design for a tile as herein shown and described.

CHARLES C. ALEXANDER.
